APPARATUS FOR INSULATING ELECTRICAL CONDUCTORS

Clyde N. Stover, Towson, Md., assignor to Western Electric Company, Incorporated, New York, N. Y., a corporation of New York

Application October 19, 1943, Serial No. 506,855

7 Claims. (Cl. 66—9)

This invention relates to methods of and apparatus for insulating electrical conductors and more particularly to methods of and apparatus for simultaneously applying a textile insulation upon a conductor and impregnating the insulation with a weatherproofing and insulating compound.

In the insulation of wire conductors with textile material, one method has consisted of knitting a covering of unimpregnated textile material upon the conductor, after which the insulating and weatherproofing material is applied to the unimpregnated material. It is difficult to impregnate material already positioned on the conductor, and as a result, the interstices in and between the individual strands of the material often are not thoroughly impregnated with the weatherproofing and insulating material. This method is also disadvantageous because of the separate equipment, time and labor necessary to perform the two operations separately. An alternate method has consisted of applying the weatherproofing and insulating material to the strands before they are placed on the conductor, but in the use of this method the strands are sticky and difficult to handle and extra time, equipment and labor are required to treat the strands.

It is an object of this invention to provide new and improved methods of and apparatus for insulating electrical conductors.

In one embodiment of this invention, a conductor to be covered with an insulating and weatherproofing jacket is passed through a knitting head which knits the strands to be applied to the conductor in the form of a cone-shaped basket, the apex of which is formed by the knitted strands tightened on the conductor. An insulating and weatherproofing compound is forced upon and between the loosely knitted strands forming the open portion of the cone-shaped textile basket. This compound thoroughly covers the knitted strands so that when they are drawn tightly around the conductor by the knitting head, the insulating and weatherproofing material completely fills all the spaces in and between the strands and thoroughly impregnates them.

A complete understanding of the invention may be obtained from the following detailed description taken in connection with the appended drawings, in which:

Fig. 1 is a side elevation of an apparatus embodying the invention by means of which methods embodying the invention may be practiced;

Fig. 2 is an enlarged, fragmentary, vertical sectional view of the apparatus shown in Fig. 1, and

Fig. 3 is an enlarged, fragmentary, vertical sectional view of an alternative form of apparatus embodying the invention.

Referring now to the drawings, an extruding head 10 is composed of an inner core tube 11 surrounded by an outer cylinder 13. The core tube 11 has formed therein a passage 12 through which a conductor 15 to be insulated and weatherproofed is advanced downwardly from a suitable source of supply (not shown). The outer cylinder 13 is concentric with the inner tube 11 and the two form an annular extrusion chamber 19 into which a viscous impregnating material 20 having insulating and weatherproofing qualities may be forced from a supply chamber 21 through a pipe 22 which connects the head 10 and the chamber 21. The impregnating material 20 may be ester gum, asphalt, rubber cement, paint, or any other well known type of waterproofing, insulating or weather resisting material. Nitrogen or other suitable gas under high pressure is supplied to the chamber from any suitable source through a valve 23 in the top of the chamber to force the impregnating material through the chamber 19. A resistance wire 24 of Nichrome or other suitable material coiled around the chamber 21, the pipe 22, and the cylinder 13 are connected in a conventional manner to a source of current 25 for heating the viscous material 20 to a temperature at which the material will flow freely through the apparatus. By using nitrogen gas as the medium to apply pressure to the hot material 20, oxidation of the material is avoided.

An inwardly positioned, inner surface 26 of the outer cylinder 13 and an outwardly curved surface 28 formed upon the exterior of the core tube 11 form an annular extrusion passage 29 through which the impregnating material 20 is forced in the form of a thin annular stream. The tube 11 is secured to an adjusting screw 30 which is threaded into the upper end of the cylinder 13. The adjusting screw 30 may be screwed farther into or out of the cylinder 13, to enlarge, diminish or close off completely the extrusion passage 29, as desired. A set screw 31 secures the plug 30 in any adjusted position.

50 A plurality of knitting needles 32—33 of conventional design are positioned on a knitting head 34 having a bore 35 therethrough, which expands into an enlarged conical opening 36 near the upper end thereof. The conical opening 36 forms with conical ends 38 and 39 on the lower

ends of the core tube 11 and cylinder 13, respectively, an annular, conical passage 40 therebetween. In the normal operation of the knitting head, the needles 33-33 form a plurality of strands 42-42 into an open, knitted cone-shaped basket 43 and the several parts of the apparatus are so related that the basket 43 is formed within the annular, conical passage 40. As the conductor 15 and the knitted covering enter the bore 35, the covering is drawn tightly upon the conductor to form a closely fitting covering 45 thereon.

In the operation of this form of the invention, the conductor 15 is drawn from a suitable supply through the passages 12 and 35 by a capstan 47. The strands 42-42 are first knitted by the knitting head 34 into the open, cone-shaped basket 43 and are then drawn tightly around the conductor 15 to form a knitted covering 45 thereon. As the open knitted basket 43 is being formed, the impregnating material 20 is forced into the interior of the basket through the extrusion passage 29, thoroughly covering the strands 42-42 thereof and filling the interstices between the individual knitted strands. As the cone-shaped basket 43 is drawn tightly around the conductor 15, the impregnating material 20 is forced into and around the individual knitted strands 42-42 by the pressure of the strands themselves and by the pressure of the conical opening 40, and the knitted covering 45 formed on the conductor 15 is thoroughly saturated and coated with the impregnating material 20. The impregnating material is cooled and hardened on the conductor 15 as the conductor passes from the capstan 47 to a suitable takeup reel (not shown).

Fig. 3 of the drawings illustrates an alternative method of applying an impregnating material to a knitted covering on a conductor as the covering is being formed. In this embodiment of the invention, an extruding head 110 consists of an inner core tube 111 surrounded by an outer cylinder 113. The core tube 111 has formed therein a passage 112 through which a conductor 115 to be insulated and weatherproofed is drawn upwardly through the apparatus by a capstan (not shown) similar to the capstan 47 shown in Fig. 1 of the drawings. The outer cylinder 113 is concentric with the core tube 111 and forms therewith an annular extrusion chamber 119 into which a viscous impregnating material 120 heated by a resistance wire 124 and having insulating and weatherproofing qualities is forced in a similar manner and from apparatus similar to that hereinabove described and illustrated in Fig. 1 of the drawings.

A curved annular surface 126 formed upon the exterior of the flared end of the core tube 111 and a complementary curved annular surface 128 formed upon the interior of the cylinder 113 together form an annular extrusion passage 129 through which the material 120 may be forced in the form of a thin, annular stream. The core tube 111 is secured to an adjusting screw (not shown) similar to the hereinabove described screw 30 and may be adjusted longitudinally with respect to the cylinder 113 to open or close the passage 129 in a manner similar to that disclosed in the description of the apparatus illustrated in Figs. 1 and 2 of the drawings. A plurality of knitting needles 133-133 of conventional design are positioned on a knitting head 134 which is also of conventional design and has a bore 135 therethrough concentric with the passage 112.

In the operation of this alternative form of the

apparatus, the needles 133-133 form a plurality of strands 142-142 into an open, knitted cone-shaped basket 143 which slides along frustoconical surfaces 138 and 139 formed on the inside of the lower ends of the core 111 and the cylinder 113, respectively, as the knitted basket is drawn upon the moving conductor 115. The conductor 115 is drawn by the capstan (not shown) through the bore 135 and passage 112 and the knitted basket 143 is drawn into a close-fitting covering 145 about the conductor 115 in the passage 112. As the basket 143 is drawn closely around the moving conductor 115, the impregnating material 120 is continuously extruded through the passage 129 into and around the loosely knitted basket 143, and the resultant knitted covering 146 formed on the conductor 115 is thoroughly saturated and coated with the impregnating material 120. The surface 138 acts as a die to force the impregnating material into the knitted covering and insures thorough impregnation thereof. The impregnating material is cooled and hardened on the conductor 115 as the conductor passes to a suitable takeup reel (not shown).

As will be readily seen, the textile material and the interstices between the individual strands thereof will be thoroughly impregnated and filled with the insulating and weatherproofing material by use of the above described methods and apparatus and the material may be applied to either the outer or the inner part of the knitted sheath, whichever is desired. This apparatus is simple in construction, yet is effective to permit conductors to be insulated rapidly and thoroughly by simple and inexpensive processes.

What is claimed is:

1. An apparatus for insulating and weatherproofing conductors, comprising a knitting head having a conical aperture therein through which a conductor may be advanced, the knitting head being designed to knit a plurality of strands into a cone-shaped textile basket about a conductor within the conical aperture and to draw the textile basket down into a tight, compact covering on the conductor, and an extruding means including a cylindrical core having a passage therein through which the conductor is advanced to the knitting head, and an outer cylinder enclosing the core and forming therewith an extruding passage through which an insulating and weatherproofing material may be extruded upon the cone-shaped basket as it is formed about the conductor.

2. An apparatus for insulating and weatherproofing conductors comprising a knitting head having a conical aperture therein through which a conductor may be advanced, and designed to knit a plurality of strands into a cone-shaped basket about a conductor and to draw the knitted textile into a tight covering around the conductor advancing through the conical aperture, and an extruding means including a cylindrical core having a passage therein through which the conductor is advanced to the knitting head and an outer cylinder enclosing the core and concentric therewith to form an extruding passage transverse to the cone-shaped basket through which to extrude an insulating and weatherproofing material upon the cone-shaped basket as it is formed about the conductor and just before the basket is drawn down on the conductor into a compact covering.

3. An apparatus for insulating and weatherproofing conductors comprising a knitting head having a conical aperture therein through which

a conductor may be advanced to knit a plurality of strands into a cone-shaped basket which is complementary to the conical aperture and is to be drawn on the conductor being advanced through the conical aperture, and an extruding means including a cylindrical core having a passage therein through which the conductor is advanced to the knitting head and an outer cylinder enclosing the core and forming therewith an annular extruding passage through which an insulating and weatherproofing material is extruded upon the inside of the basket as it is drawn on the conductor.

4. An apparatus for insulating and weatherproofing conductors comprising a knitting head having a conical aperture therein through which a conductor may be advanced to knit a plurality of strands into a cone-shaped basket which is drawn tightly about the conductor being advanced through the conical aperture, and an extruding means including a cylindrical core having a passage therein through which the conductor is advanced to the knitting head and an outer cylinder enclosing the core and forming therewith an annular extruding passage to extrude an insulating and weatherproofing material upon the outside of the basket as it is drawn about the conductor.

5. In an apparatus for applying protective coverings to conductors, means for forming a cone-shaped textile covering around a conductor, means for advancing a conductor through the forming means to draw a covering formed thereby tightly upon the conductor, and an extruding means including a cylindrical core tube through which the conductor is advanced, an outer cylinder enclosing the core tube and forming therewith an annular extrusion passage spaced from and concentric with a conductor drawn through the core tube, means for forcing a plastic im-

pregnating material through the extrusion passage, whereby an annular stream of impregnating material is extruded upon the covering before the covering is drawn tightly upon the article, and means for adjusting the size of the extrusion passage.

6. In an apparatus for applying protective coverings to conductors, means for forming textile strands into a covering in the form of a cone-shaped basket around a conductor, means for advancing a conductor through the forming means to draw a covering formed by the forming means closely upon the conductor, and an extruding means positioned between the forming means and the advancing means, said extruding means including a core tube, an outer cylinder positioned around the core tube and cooperating therewith to form an annular passage directed substantially perpendicularly to the cone-shaped portion of the covering for directing a liquified impregnating material substantially perpendicularly against that portion of the covering, and means for adjusting the position of the core tube relative to the cylinder to vary the size of said passage.

7. In an apparatus for applying protective coverings to conductors, means for forming strands into a covering in the form of a cone-shaped basket around a conductor, means for advancing a conductor through the forming means to draw closely upon the conductor a covering formed by the forming means, a tubular extruding means provided with an annular extruding passage concentric with and spaced from the conductor to direct an annular sheet of impregnating material upon the more open portions of the cone-shaped basket, and means for forcing a liquified impregnating material through the extruding means.
